Primary Examiner — Marianne N. Pandozzi*Assistant Examiner* — Jae Liang(74) *Attorney, Agent, or Firm* — DWC Law Firm, P.S.;
David Chen(57) **CLAIM**

The ornamental design for a mixer bottle for drinking liquids, as shown and described.

DESCRIPTION

FIG. 1 is a top perspective view of a mixer bottle for drinking liquids showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is an enlarged top view thereof;

FIG. 7 is an enlarged bottom plan view thereof; and,

FIG. 8 is a rear elevational view thereof with a tether attached.

The broken lines in the figures depict portions of the mixer bottle for drinking liquids that form no part of the claimed design.

1 Claim, 7 Drawing Sheets(56)
